UNITED STATES PATENT OFFICE.

JAMES JACKSON, OF NEW YORK, N. Y.

REFRIGERATOR.

SPECIFICATION forming part of Letters Patent No. 296,573, dated April 8, 1884.

Application filed December 17, 1883. (No model.)

To all whom it may concern:

Be it known that I, JAMES JACKSON, of the city and State of New York, have invented an Improvement in Refrigerators, of which 5 the following is a specification.

Refrigerators have been made with ventilating-openings near the top of the ice-box, into which air passes and is cooled as it descends, and often there are one or more openings at the bottom of the refrigerator through which the water escapes.

In refrigerators that have heretofore been made there is considerable loss of cooling power, because the air circulates very slowly, 15 especially after the temperature of the cooling-chamber has been reduced, because there is but little difference between the gravity of the air in the ice-chamber and that in the cooling-chamber.

20 I make use of a ventilating-tube rising from the bottom of the refrigerator toward or into the ice-chamber, and a damper may be applied to said tube, so that there will be a downward escape of air from the ice-chamber to the external atmosphere sufficient to promote a circulation of the air throughout the entire refrigerator, and impure air will flow away by this ventilating-tube, and amount of escape-air will be regulated by the damper, according 25 to character of the substances that are being refrigerated.

In the drawing I have represented the refrigerator by a vertical section.

The sides *a*, bottom *b*, top *c*, and ice-chamber *d* are to be of ordinary character, and doors are to be provided, as usual, for giving access to the ice-chamber and the cooling-chamber *e*. The partition *f* separates the ice-chamber from the cooling-chamber *g*, and *h* is 30 the bottom of the ice-chamber. The ventilating-pipe *k* passes through the bottom *b* of the refrigerator, and it extends up about half the height of the cooling-chamber *e*, and a damper, *i*, may be applied in said pipe, the stem of 35 which passes through the side of the refriger-

ator, so as to be easily turned to regulate the extent of the escaping ventilating-current of air. It will be evident that the coldest air will not escape by this ventilating-pipe *k*, because the coldest atmosphere descends to the 50 bottom of the cooling-chamber. The atmosphere, which is charged with vapors and odors from the materials in the cooling-chamber, will be found in said chamber at about the level of the top of this pipe, and will flow away 55 from the chamber by this pipe, so as to keep the refrigerator sweet and the viands therein wholesome, and the current of air descending through this pipe by gravity will escape, and thereby give sufficient exhausting action to 60 insure a constant circulation of the air in the refrigerator and prevent the atmosphere therein becoming stagnant.

Although a portion of the cool air of the refrigerator may be wasted by passing out of 65 the same, I have found that the loss is more than compensated by the increased efficiency of such refrigerator.

I do not claim a tube with an opening below the refrigerator to convey away water of condensation; neither do I claim a tube the upper end of which is at or near the level of the bottom of the ice-chamber to convey the cold air to a cooling-chamber.

I claim as my invention—
75 The combination, with the ice-chamber and the cooling-chamber in a refrigerator, of a ventilating-pipe opening at its lower end to the exterior atmosphere, and rising within the cooling-chamber to about the middle of the 80 same for confining the cold air and for allowing the escape by a downward circulation of a portion of the air within the refrigerator, for the purposes, and substantially as set forth.

Signed by me this 11th day of December, 85
A. D. 1883.

JAMES JACKSON.
